FIG. 1 is a front view showing my new design of an insect trap. It is to be understood that the composite star and leaf cluster display which is partially shown in full lines continues uniformly throughout the areas designated by the intersecting broken lines;

FIG. 2 is a top plan view of the trap;

FIG. 2 is a top plan view of the trap;
FIG. 3 is a bottom plan view of the trap;

FIG. 3 is a bottom plan view of the trap; FIG. 4 is a view looking at the right-hand side of FIG. 1. The left-hand side view is opposite hand to the side view shown;

FIG. 5 is a sectional plan view taken along line 5—5 in FIG. 1;

FIG. 6 is a sectional plan view through the front panel of the trap and taken along line 6-6 in FIG. 1;

FIG. 7 is an enlarged fragmentary view of the star and leaf cluster display shown in FIG. 1; and

FIG. 8 is an enlarged fragmentary sectional view taken along line 8—8 in FIG. 1.

I claim:

The ornamental design for an insect trap, as shown and described.
